CLAIM

We claim the ornamental design for an asset tracking equipment housing, as shown and described.

DESCRIPTION

FIG. 1 is a bottom perspective view of an example asset tracking equipment housing;

FIG. 2 is a top perspective view thereof;

FIG. 3 is a front view thereof;

FIG. 4 is a rear view thereof;

FIG. 5 is a first side view thereof;

FIG. 6 is a second side view thereof;

FIG. 7 is a bottom view thereof; and,

FIG. 8 is a top view thereof.

Broken lines of a particular embodiment are for purposes of illustrating environment and form no part of the design claimed in that embodiment.
